CONVEYING MECHANISM FOR FURNACES
AND THE LIKE

Edward N. Millan and Percival C. Jones, Middletown, Ohio, assignors to The American Rolling Mill Company, Middletown, Ohio, a corporation of Ohio

Application February 18, 1932. Serial No. 593,816

5 Claims. (Cl. 263—6)

Our invention relates to mechanism adapted for the non-continuous conveying of materials or articles through a treating zone or device; and while our invention is not restricted to the specific embodiment hereinafter described, either as to exact construction or the manner or circumstances of its use; we will describe it for the purpose of making a disclosure, as applied to a heating furnace in which sheets or other articles are heat treated preparatory to rolling or other working treatments. Such furnaces are usually of tunnel-like construction, having an entrance at or near one end, and an exit at or near the other, and they are equipped with some sort of conveying mechanism designed to cause sheets, or other articles, to pass through them to be heat treated and to be delivered at the far end, preferably under controlled conditions of temperature and time of delivery.

It is an object of our invention to provide an improved conveyor mechanism for carrying materials or articles through a treatment zone.

As applied to furnaces, it is an object of our invention to secure better heat distribution in the furnace and a more uniform heating of the articles being treated, such as packs, bars, sheets and the like.

It is an object of our invention to prevent undue loss of heat carried out of the furnace by conveyor mechanisms.

It is also our object to provide means for delivering articles, sheets, or the like, without cold spots.

It is still another object of our invention to provide conveying mechanism which is adequate to the ends hereinabove mentioned, and which at the same time is adapted for the movement of sheets, articles, or the like, without detriment to such articles.

More specifically it is an object of our invention to provide in connection with conveying means, supporting means within the furnace, permitting both the even heating of the pieces and the return of the conveyor portions which have necessarily been removed from the furnace in the delivery of an article. Another specific object is to secure these functions and advantages in a structure which nevertheless is capable of rapid removal of pieces from the furnace so that a cyclical operation does not control the speed with which the furnace may be filled with or emptied of pieces to be heat treated.

These and other objects of our invention which will be set forth hereinafter or will be apparent to one skilled in the art upon reading

our specifications, we accomplish by that certain construction and arrangement of parts of which we shall now describe the aforesaid exemplary embodiment, it being understood that our invention is not restricted thereto, nor to the hereinafter described circumstances of use, but is capable of other uses and may be modified by those skilled in the art without departing from the spirit thereof. Reference is now made to the drawings, wherein:

Figure 1 is a longitudinal vertical section through an exemplary furnace embodying our invention.

Figure 2 is a transverse sectional view thereof.

Figure 3 is an elevation of a drive mechanism.

Figure 4 is a plan view of said drive.

Figure 5 is a spread out diagram of the connections.

Figure 6 is a cam type limit switch geared to sprocket similar to 4, except on the front end of the furnace (not shown in Fig. 1), properly timed through suitable gear reduction.

Figure 7 is a cam type limit switch mounted on the shaft of the reducer 31.

Briefly, in the practice of our invention, we provide a conveying mechanism, in the furnace, capable of continuous controlled movement, and we likewise provide within the furnace means for lifting the sheets or articles from the conveyor, whereby the conveyor may be reversed and the heated portion thereof brought back into the furnace as desired. The means for lifting the sheets or articles from the conveyor comprise means affording a satisfactory support for said sheets or articles in the heated zone; and since these supports remain in the furnace at all times, we secure the advantage of heat retention, rendering the furnace more efficient; and we also are enabled to heat treat the sheets or articles evenly, and without the formation of cold spots due to a conveyor mechanism which is not at furnace temperature. In the particular type of furnace shown a chain conveyor is provided, the chain portion of which in the upper or forward traveling part is preferably located within or beneath the floor of the furnace, there being provided conveyor arms or fingers which extend through said floor. Driving means for this conveyor will be located outside the furnace, as will likewise be driving means for the lifting devices, the operating means for said lifting devices being preferably located beneath the floor of the furnace. Since our lifting devices move vertically through the furnace floor,

90
95
100
105
110

it is not necessary for us to provide elongated openings through said floor.

- In the movement of pieces through the furnace, the lifting devices first lower the pieces onto the conveyor, and the conveyor then carries the pieces forward a desired distance. The pieces are then raised by the lifting devices from the conveyor. A cyclical operation of this sort is contemplated and is maintained as will hereinafter be more fully described; but the cycle has nothing to do with the length of movement of the conveyor proper, and consequently our furnace may be filled or emptied as rapidly as may be desired.
15. In Fig. 1 we have shown a furnace indicated generally at 1, having a floor 2. The portions of this furnace have been shown diagrammatically since they will be well understood by those skilled in the art and do not need special disclosure. A conveyor has been indicated diagrammatically in Fig. 1 at 3. One of the end sprockets for this conveyor has been indicated diagrammatically at 4; and at 5 there has been indicated a feeding table adapted to deliver sheets, packs, bars, or other articles, to the conveyor aforesaid.

In Fig. 2 it will be seen that the conveyor comprises chain members 6, preferably located as shown within the floor of the furnace. These chain members may be provided with anti-friction devices such as rollers 7 operating in channel iron tracks 8 within the furnace floor, and the various links of the conveyor chain will be provided with upstanding conveyor arms or fingers 9. These extend through slots 10 in the furnace floor, and in order to be able to withstand the heat of the furnace they will preferably be made of some heat resisting alloy, as is well known in this art. The conveyor returns beneath the furnace as shown at 11, where the links ride in suitable brackets 12 fastened upon supports 13. The sprockets of the conveyor, usually one at each end of the furnace, will be arranged with a suitable power drive such as an electric motor.

Beneath the furnace floor (which as shown in Fig. 1 is supported upon suitable beams 14, or the like), we provide a beam or bar 15, which is mounted for vertical reciprocation upon pins or rollers 16, riding in supporting members 17, having yokes 18. As many of the bars 15 will be provided as may be found necessary. The bars preferably extend longitudinally of the furnace, and preferably also are interconnected by cross beams 19, forming therewith a framework. Upon this framework we mount vertically extending arms 20. These arms pass through holes 21 in the furnace floor, but since they can move only vertically, these holes need be very little larger than the arms themselves, and they may additionally be closed by washer members 22, either fixed on the arms or slidably with reference thereto. This washer and the arms themselves will preferably be made of heat resisting alloy. The arms may bear at their upper ends common supporting bars 23 extending longitudinally of the furnace and adapted to support sheets or articles therein and, when the arms are thrust vertically, to raise such sheets or articles from the arms 9 of the conveyor chains. As very clearly shown in Fig. 2, these arms are arranged sidewise of the conveyor chains; and when the bars 23 are employed they will form supporting lines between which the conveyor

chain arms 9 may travel. Obviously as many of the arms 20 and supporting members within the furnace may be employed as are found necessary to provide the requisite support.

The bars 23 form supporting means for sheets or articles, adapted either to hold them stationary above the conveyor, or to lower them into position for movement by the conveyor. The vertical reciprocation of the arms 20 is determined by the beams 15, which are guided for vertical movement upon the members 17. Mechanical or other means are provided for the actuation of the beams.

We have found it very satisfactory to provide a series of bell cranks, pivoted to suitable pivot members 24 upon a foundation or other support. One arm 25 of these bell cranks is connected by a linkage member 26 to the beam 15 at a pivot member 27. The other arm 28 may be pivoted to a connecting rod or rods 29. Movement of this connecting rod, tending to cause the bell cranks to turn in a clockwise direction, will raise the beams 15 and the supporting members within the furnace.

To the end of effecting controlled movement of the bell cranks, we provide a source of power such as an electric motor 30 or the like, which, through an appropriate gear reduction mechanism 31, where necessary, may be caused to transmit power to a main shaft 32. This shaft may be mounted in bearings 33 on the foundation; and we prefer to mount a lever 34 on the shaft, and to connect this lever by a linkage member 35 to a lever 36 on the drive shaft of the speed reducer 31. The length of the levers is so proportioned that when the shaft of the speed reducer rotates through a complete turn, the shaft 32 will be rocked and returned through the desired arc for the actuation of the beams 15. Lever arms 37, non-rotatably mounted upon the main shaft 32, are operatively connected to the connecting rod 29. The levers 37 may, if desired, be part of bell cranks having additional lever arms 38 connected to the beams 15 by linkages 39.

Since the weight of the frame and supporting members forming the assembly attached to the beams 15 is considerable, we prefer to counterweight it by means of weights 40 on cables 41.

The cables pass over sheaves 42 and are connected to the lever arms 34 or other suitable lever arms on the shaft 32.

The feeding table 5 serves to support sheets or pieces, prior to feeding, out of contact with the conveyor 3. A run-out table of suitable form will usually be provided at the exit end of the furnace as at 43; and where this table overlies the conveyor 3, it is convenient to mount it, or a portion of it at least, upon the beams 15, so that a reverse movement of the conveyor will not drag the delivered sheet or article back toward the furnace.

The operation of our device is as follows: Assuming that the furnace is full of pieces, and that the supporting members 23 are holding these pieces away from contact with the conveyor, the motor 30 is first started. When started the driving mechanism will be in the position shown in Fig. 3. The shaft 32 will be rocked in a counterclockwise direction, the lever 36 passing through a half revolution for the purpose. This drops the framework and support assembly attached to beams 15, lowering the pieces or articles onto the conveyor arms 9.

The motor 30 will then be stopped, and a source of power connected with the conveyor 3 will be started, driving the conveyor in the forward direction through a desired distance, which will usually be at least sufficient to deliver a piece from the furnace, but may be as much longer as desired. At the same time, another piece may be fed onto the conveyor 3 from the feeding table 5, and carried into the furnace. When a piece has been delivered from the furnace the conveyor 3 will of course be stopped. If this operation has resulted in carrying the next piece in line out of the heating zone, the next operation may be the reversal of conveyor 3 for a predetermined length of travel. When the pieces remaining in the furnace are properly positioned the conveyor is again stopped. The motor 30 is next started, and is allowed to run until lever 36 has returned to the position shown in Fig. 3. This raises the supports 23, lifting the pieces from the conveyor. The motor 30 is then stopped. Afterward conveyor 3 may be run in the reverse direction sufficiently to return to the furnace the heated portion of the conveyor elements. The cycle is repeated for each piece or series of pieces to be delivered into or out of the furnace; but the cycle does not limit the length of travel of the conveyor 3, and the furnace may be entirely filled or entirely emptied at one operation. Or in any one operation as many pieces as desired may be serially delivered from the furnace in one cycle.

It will be clear that by means of appropriate relays and limit switches the operations of motor 30 may be caused to have a fixed relationship to the operations of the conveyor 3. Thus a starting button may be provided which will initiate automatic operations as follows: the starting of motor 30 so as to lower the pieces onto the conveyor; the stopping of motor 30 when this is done; and the starting of the motor or other prime mover attached to conveyor 3. A stopping button may be provided to initiate operations as follows: the stopping of conveyor 3, the starting of motor 30 whereby the pieces are again lifted from the conveyor; the stopping of motor 30; and if desired, the reversing of conveyor 3 and the stoppage thereof after a predetermined travel. Or separate reversing controls may be provided for the conveyor. If a preliminary reversing of the conveyor is desired prior to the removal of the pieces therefrom, this may, by appropriate limit switches, be provided as an automatic part of the cycle.

In this way the operations of the lifting and supporting elements of our furnace may be so arranged with respect to the control of the conveyor that the manual operation thereof by a series of control buttons, or the like, will be as simple as the operation of a furnace having nothing but the chain conveyor. Under some circumstances the full automatic operation of the furnace may be desired, or some type of semi-automatic operation in which the movements of the articles through the furnace are determined by some specific condition or conditions. Thus the cycle of operations may be started by a time clock to operate a starting switch, or it may be started by a pyrometer control effected by the temperature of the article, sheet or pack. A particular advantage of our invention resides, however, in the fact that the length of movement of the conveyor in either direction need not be fixed with rela-

tion to the movements of the lifting and supporting devices, even though the lifting and lowering of pieces within the furnace may be rendered automatic with respect to starting, stopping, or reversing operations of the conveyor. Where the furnace is to be employed for the heating of sheets or packs for hot rolling, and where the length of these sheets or packs may vary, it is convenient to have the cycles of operation (whether started by hand or by time clock) determined by the length of the piece or pack passing through the furnace. A furnace control system adequate to this end is described as follows, with reference to Figures 5, 6 and 7:

The switch 50 is closed only when the arms 20 are in up position. The switch 51 is closed as soon as there is an appreciable downward movement of the arms 20 and remains closed until the arms 20 reach top position. The switch 52 is closed when the arms 20 are in up position and remains closed until the arms 20 reach bottom position. The switch 53 closes and opens again just before the arms 20 reach the top position. The switch 54 closes just before the arms 20 reach the bottom position and opens when the arms 20 have reached the bottom position. The switch 55 closes and opens again when there is an appreciable upward movement of the arms 20. The switches 56, 57 and 58 are closed when the furnace 1 is fully charged with packs and open when there is an appreciable amount of forward travel of the conveyor 3. The switches 59 and 60 close when there is an appreciable amount of forward travel of the conveyor 3, and are open in the starting position. The switch 61 closes when the pack hits the trigger 44. The switch 62 is connected to the trigger 44 in such a way that the switch 62, 62' is closed when the pack hits the trigger, and the switch 62, 62'' is closed when the trigger is not in contact with the pack. Latching relays are indicated by the numerals 63 and 64. The switch 65 is a control switch for the non-automatic operation of the conveyor 3 for filling the furnace with packs when starting operation and the like. The numerals 65' and 65'' indicate the forward and reverse position of the switch 65. The selector switch for automatic or non-automatic operation of the furnace is indicated by the numeral 66. 66' and 66'' indicate the automatic and non-automatic position of the switch 66. The foot switch for the operator is indicated by the numeral 67. The switch 68, if desired, may be used in place of the foot switch 67. The switch 68 is actuated by a circuit which is controlled by a clock in order that a pack may be delivered from the furnace to the mill automatically, at chosen and constant intervals. The switch 69 is a contactor switch in the circuit of the motor 30. A magnetic coil 69', when energized, closes the switch 69. The switch 69'' is actuated by the magnetic coil 69'. This switch is open when the switch 69 is open, and closed when the switch 69 is closed. The switch 70 is a forward contactor switch in the circuit of the motor 78. The switch 71 is a reverse contactor switch in the circuit of the motor 78. The magnetic coils 70' and 71', if energized, close the switches 70 and 71, respectively. The switches 70'' and 71'' bear the same relation to the switches 70 and 71, respectively, as the switch 69'' does to the switch 69. An overload coil of overload relay 72 is in circuit with the motor 78. An

overload coil of overload relay 73 is in circuit with the motor 30. The numeral 74 represents an emergency stop button, and there is a safety switch 75 in the circuit of the motor 78 and a safety switch 76 in the circuit of the motor 30. The power supply is generally indicated by the numeral 77. A motor 78 drives the chain conveyor 3.

The sequence of operation is as follows: A controller or clock closes the switches 67 or 68 as desired. The coil 69' is energized through the switches 50, 56 and 73'. The contactor 69 and the switch 69'' close. The arms 20 move downwardly. The cam type limit switch (Fig. 7) moves in a clockwise direction. The first switch 50 opens, then the switch 51 closes. The coil 69' is still energized through the switches 52, 57 and 69''. The switch 54 closes. Then the switches 52 and 54 open, deenergizing the coil 69'. The arms 20 stop in the down position. The closing of the switch 54 energizes the coil 70' which closes the contactor switch 70 and the switch 70''. The chain conveyor 3 moves in a forward direction. The closing of the switch 54 also energizes the coil 64' of the latching relay switch 64. This establishes a holding circuit for the coil 70', and, although the switch 54, opens again the coil 70' remains energized.

30 The pack hitting the trigger 44 closes the switches 61 and 62-62'. The switch 61 establishes a parallel holding circuit for the coil 70' and also energizes the unlatching coil 64'' of the relay 64. The contacts of the relay 64 open. The switch 62-62' energizes the coil 63' of the latching relay 63, but at this time does not establish a circuit, since the switch 62-62'' is open. The cam type limit switch (Fig. 6) which is geared to the conveyor sprocket shaft 40 on the front end of the furnace begins to turn in a clockwise direction. The switches 56, 57 and 58 open first, then the switches 59 and 60 close. As the rear end of the pack clears the trigger 44, the switches 61 and 62-62' open. The coil 70' is deenergized and the contactor 70 and the switch 70'' open. The chain conveyor 3 stops. The switch 62-62'' is now closed, which energizes the coil 69' through the contacts of the relay 63. The contactor 69 and the switch 69'' close. The arms 20 move upwardly. The cam type limit switch (Fig. 7) moves in a clockwise direction. The first switch 55 closes and then opens again, thereby energizing the unlatching coil 63'' of the relay 63. 55 The relay 63 opens, but the coil 69' remains energized through the switches 51 and 59. As the arms 20 approach the top position, the switch 50 closes, then the switch 52 closes, and finally at the end position the switch 51 opens. The coil 69' is deenergized and the contactor 69 and the switch 69'' is open. The motor 30 then stops, and the arms 20 are stopped in their top position. Just before reaching the top position, the switch 53 closes and then opens again. This energizes the coil 71' and the contactor 71 and the switch 71'' closes. Thus, the chain conveyor 3 moves in a reverse direction. The cam type limit switch (Fig. 6) moves in a counter-clockwise direction and the switches 59 and 60 open. The switch 60 deenergizes the coil 71' and the contactor 71 and the switch 71'' opens, thereby stopping the motor 78. The switches 56, 57 and 58 close again, completing the cycle.

70 75 Upon closing of the foot switch 67 or the timed

contact 68, the above described cycle of operation will be repeated.

Having thus described our invention, what we claim as new and desire to secure by Letter Patent, is:

1. In a furnace or other zone treating device, a chain conveyor mechanism having laterally spaced, longitudinal, flexible elements provided with work carrying fingers, vertically reciprocable rail elements positioned in the interspaces between said spaced elements, supporting means attached below said rail elements, said rail elements being adapted to raise articles from said fingers and to lower articles thereon, said supporting elements adapted to be lowered into said interspaces so as to bring said rails below the tops of said fingers.

2. In a furnace, or the like, a conveyor comprising a plurality of laterally spaced, longitudinal, flexible elements provided with work carrying fingers, vertically reciprocable rail elements between said spaced elements, supporting means attached below said rail elements, said rail elements being arranged to be lowered between said spaced elements to below the top of said fingers, or to be raised above the top of said fingers, and driving means for reciprocating rail elements.

3. In a furnace, or the like, a conveyor comprising a plurality of laterally spaced, longitudinal, flexible elements, vertically reciprocable rail elements located in the interspaces between said spaced elements, a frame below said rail elements and to which said rail elements are attached, means for guiding the vertical reciprocation of said frame, and means for causing said frame to move vertically.

4. In a furnace, or the like, a conveyor comprising a plurality of laterally spaced, longitudinal, flexible elements, vertically reciprocable rail elements located in the interspaces between said spaced elements, a frame below said rail elements and to which said rail elements are attached, means for guiding the vertical reciprocation of said frame, and means for causing said frame to move vertically, said means comprising a source of power and an operative connection between the same and said frame, a source of power for said conveyor and electrical control means for interrelating the movements of said conveyor and said rail elements.

5. In combination with a furnace having a floor, chain conveyor elements having substantially parallel upper laps disposed below the upper surface of said floor and having supporting elements extending above said surface, vertically reciprocating members located between said conveyor elements, a frame to which said members are attached, said frame being below said floor, means for vertically reciprocating said frame, rails attached to said members, said rails extending in the direction of said conveyor elements, a source of power motion transmitting means for lifting said frame, vertical guiding means for said frame, and an operative connection between said source of power and said motion transmitting means, a source of power for said conveyor and control means for effecting the sequential operation of said several power sources.
